UNITED STATES PATENT OFFICE.

ARTHUR W. SMITH, OF NEW YORK, N. Y., ASSIGNOR TO REMINGTON TYPEWRITER COMPANY, OF ILLION, NEW YORK, A CORPORATION OF NEW YORK.

TYPE-WRITING MACHINE.

1,106,898.

Specification of Letters Patent. Patented Aug. 11, 1914.

Application filed April 3, 1913. Serial No. 758,348.

To all whom it may concern:

Be it known that I, ARTHUR W. SMITH, a citizen of the United States, and resident of the borough of Manhattan, city of New York, in the county of New York and State of New York, have invented certain new and useful Improvements in Type-Writing Machines, of which the following is a specification.

10 My present invention relates to line spacing mechanism for typewriting machines and its principal object is to provide new and improved mechanism of the character specified.

15 To the above and other ends, my invention consists in the features of construction, combinations of devices, and arrangements of parts hereinafter described and particularly pointed out in the claims.

20 In the accompanying drawing which illustrates one form of my invention, Figure 1 is a fragmentary plan view of one end of a platen carrier and a platen showing my invention applied thereto. Fig. 2 is a trans-

25 verse sectional view taken on a vertical plane indicated by the dotted line α in Fig. 1 and looking in the direction of the arrow at said line, the ratchet wheel being shown in dotted lines and the mounting of the 30 platen carrier also being shown. Fig. 3 is a perspective view of part of the line spacing mechanism. Figs. 4, 5 and 6 are fragmentary operating views of some of the parts looked at as in Fig. 2.

35 Referring first to Figs. 1 and 2, the main frame of the machine comprises a top plate 1 having a depressed portion or trough 2 wherein are secured oppositely grooved

40 guide rails 3 which coöperate through anti-friction balls 4 with the opposite grooved faces of a slide bar 5 comprised in a platen frame or carriage, which further includes end bars 6 and a connecting cross bar or rod 7. The end bars provide bearings for the

45 axle 8 of a rotary platen 9, said axle being provided with the usual knobs or finger wheels 10. Operatively connected with the right-hand end of the platen is a line spacing ratchet wheel 11 with the top of which

50 engages a roller detent 12 mounted on a spring arm 13 secured by a screw 14 to the platen carrier. The right-hand end bar 6 is formed with an opening 15 having a forward extension 16 narrower than the main

55 opening.

Extending rightward from the right-hand end bar above and below the narrow opening or extension 16 are ears or lugs 17 which receive a detachable shouldered screw 18 that provides a pivot for a pawl carrier 60 or line spacing actuator. The pivot 18 is vertically disposed in rear of the platen axle and at right angles to the platen axle which is horizontal, the pivot being also to the right of the ratchet wheel 11, which 65 in turn is at the right-hand end of the platen and is in a vertical fore and aft plane.

The pawl carrier in the present instance is in the form of a one-piece bell crank lever, indicated as a whole by the numeral 19, the 70 longer arm 20 whereof extends forward under the platen axle and inclines slightly upward to fully clear the top plate, terminating at its free end in a finger portion 21.

The arm, handle or hand piece 20 extends 75 from and is integral with a hub portion 22 which is best shown in Fig. 3, said hub portion being formed with a vertical bearing opening 23 to fit over and bear on the pivot screw 18. The shorter arm 24 of the bell 80 crank 19 extends horizontally inward toward the ratchet wheel 11, terminating behind the same. At the free end of the shorter arm 24 is a vertically disposed ex-

85 tension or abutment 25 which is adapted to 90 coöperate with the ratchet wheel at its rear and under side to limit the operating movement of the pawl carrier or bell crank 19, the latter swinging in a substantially horizontal path from left to right, transversely 95 of the plane of the ratchet wheel 11. A coiled restoring spring 26 is hooked at its forward end into nicks or depressions 27 on the abutment 25, the rear end of said

spring being anchored to a pin 28 on the 100 end bar 6 (Fig. 2). This spring returns the pawl carrier and parts mounted thereon from right to left to normal position after operation and normally maintains the arm 20 engaged with a resilient stop 29 of rubber or the like projecting outward from the end bar 6 (Fig. 1). The arm 24 provides

105 a support for a vertically disposed pawl 30 which is pivoted on a horizontal pivot screw 31 to the forward face of the arm 24, said pawl extending inward along said arm and being formed on its free end with a tooth

110 32 which is adapted to engage with the teeth of the ratchet wheel at the under side thereof but normally is separated therefrom.

A wire spring 33 is secured by a screw 34 to the under side of the arm 24, said spring engaging at its free end with the under side of the pawl 30 and tending constantly to 5 swing it upward in a substantially vertical plane about its axis which is coincident with the axis of the screw 31. The upward movement of the pawl is limited by a regulating device, which in the present instance is in 10 the form of a horizontally movable lever 35 pivoted on a vertical screw 36 to the top of the arm 24. The lever 35 has an outward extending finger piece 37 which is readily accessible from behind the hub 22 of 15 the carrier, said finger piece forming one arm of said lever 35. The other arm 38 of the lever 35 is bent to provide stop portions or devices 39 and 40 for coöperation with the upper face of the pawl 30.

20 The stop faces or devices 39 and 40 are at different heights or elevations, the stop 39 being lower than the stop 40, as is apparent from Fig. 2, and as will be clearly understood from a comparison of Figs. 4 and 5.

25 When the regulator or lever 35 is positioned, as in Fig. 4, the stop portion 39 will overlie the pawl 30, which will be maintained by its spring 33 normally engaged therewith. By pressing the finger piece 37 rearward the lever 35 may be swung on its pivot to carry the stop portion 39 forward out of engagement with the pawl 30 and to bring the stop portion 40 vertically over the same as in Fig. 5. This permits the spring 33 30 to swing the pawl upward into engagement with the stop portion 40 so that the tooth 32 is normally higher. The portion of the arm 38, which joins the stop portions proper 39 and 40, is inclined so that it may 35 act as a cam on the pawl 30, the result being that when the finger piece 37 is pulled forward to its first position the pawl 30 will be forced downward until it is again in the Fig. 3 position. It will be seen that the 40 regulator 35 and the spring 33 provide in combination means for variably regulating and setting the normal height of the pawl tooth 32. The purpose and effect of this variation in the normal location of the 45 pawl tooth will be understood from a comparison of Figs. 4 and 5.

When the pawl tooth is set normally as in Fig. 4 it will, when swung forward during a line spacing operation, engage with the 50 tooth *a* of the ratchet wheel 11. This forward movement of the pawl is of course due to a rightward swinging movement of the pawl carrier or bell crank 19 about the screw or axis 18, due to rightward pressure applied to the finger piece 21, for the purpose both of line spacing the platen and of restoring the carriage from left to right to begin a new line. It may be stated that in the present instance the resistance of the 55 spring mounted detent 12 is such that the

line spacing may be effected prior to the beginning of the return movement of the carriage. As a result of engaging with the tooth *a* of the ratchet wheel the pawl tooth 32 will, when the parts are arrested as in 70 Fig. 6 by engagement of the abutment 25 with the ratchet wheel 11, have turned or advanced the platen a unit of line space distance as measured by the distance from one tooth to another of the ratchet wheel 11 75 under control of the spring mounted roller detent 12. When the pawl tooth 32 is set, as in Fig. 5, it will under a line spacing operation be swung forward to engage with the tooth *b* of the line spacing wheel, which 80 is the next tooth in rear of the tooth *a*, and as a consequence the platen will be advanced two units of line space distance, as measured by the space between one tooth of the ratchet wheel 11 and the second tooth following. 85 Whether advanced a distance of one or two teeth the ratchet wheel and pawl will be in the relation shown in Fig. 6 when the parts are arrested by the engagement of the abutment 25 with said ratchet wheel. The 90 difference in extent of line spacing advance corresponds, it will be perceived, to the difference in the extent of the lost motion between the pawl 30 and the tooth of the ratchet wheel with which it engages. In 95 one instance the pawl tooth 32, in moving from the normal position of Fig. 4 to the point of engagement with the tooth *a*, will move idly through a space measured in part by the longer face of the tooth *b*, said pawl 100 moving along under said tooth *b* without affecting the line spacing wheel. In the second instance, however, the pawl tooth before engaging with the tooth *b* will move from the normal position in Fig. 5 idly only 105 a short distance, and consequently a large portion of the movement of the pawl tooth that was wasted in the first instance will be employed in turning the ratchet wheel, resulting in an advance thereof twice as great 110 in extent as in the first instance.

It will be observed that by my present invention a line spacing mechanism is provided which while highly efficient is extremely simple in construction and comparatively cheap to manufacture. The working parts, aside from the springs, are only three, namely, the pawl carrier or lever 19, the pawl 30 and the regulator 35. Two of these parts, the pawl and the regulator, are 115 mounted on the third part, as is also the pawl spring 33. By removing the bearing screw 18 and disconnecting one end of the securing spring 26, the entire line space actuating mechanism may be removed from 120 the machine; and of course it may be as readily replaced.

Various changes in details of construction may be made without departing from my invention.

What I claim as new and desire to secure by Letters Patent, is:—

1. In a typewriting machine, the combination of a platen, a connected line spacing wheel, a pawl carrier pivoted on a vertical axis in rear of the platen axis, a pawl pivoted on said carrier, said pawl having a horizontal axis of rotation, and a device on said carrier for regulating normally the vertical position of the engaging tooth of said pawl. 5
  2. In a typewriting machine, the combination of a platen, a line spacing ratchet wheel connected thereto, a hand operated pawl carrier arranged under the platen axle and pivoted to swing in a path substantially parallel thereto, and a pawl on said carrier variably settable in a vertical plane to vary the effective stroke of said pawl, said pawl being adapted to coöperate with said ratchet wheel 15 but being normally separated therefrom. 20
  3. In a typewriting machine, the combination of a platen, a line spacing ratchet wheel connected thereto, a hand operated pawl carrier arranged under the platen axle and pivoted to swing in a path substantially parallel thereto, a pawl on said pawl carrier pivoted to swing in a vertical plane, said pawl being adapted to engage with said ratchet wheel at the under side thereof in rear of a 25 vertical plane passing through the platen axle, and means for varying the height at which the tooth of said pawl is normally located. 30
  4. In a typewriting machine, the combination of a platen, a line spacing ratchet wheel connected thereto, a hand operated pawl carrier arranged under the platen axle and movable in a path substantially parallel thereto, a pawl on said pawl carrier pivoted to swing in a vertical plane, a pawl spring tending constantly to swing said pawl upward, said pawl being adapted to engage with said ratchet wheel at the under side thereof in rear of a vertical plane passing 40 through the platen axle, and means for varying the height at which the tooth of said pawl is normally located, said means comprising a device pivoted on said pawl carrier and swingable to permit said pawl spring to raise said pawl to different heights. 45
  5. In a typewriting machine, the combination of a platen carrier, a platen thereon, a line space ratchet wheel arranged at the right of said platen and operatively connected thereto, a pawl carrier pivoted on a vertical axis, said axis being to the right of said ratchet wheel and in rear of the platen axle, a pawl pivoted on said pawl carrier to swing in a vertical plane, said pawl being adapted 55 to coöperate with the under side of said ratchet wheel, a spring tending constantly to swing said pawl upward, and means for regulating the normal height of the pawl tooth. 60
  6. In a typewriting machine, the combination of a platen carrier, a platen thereon, a line space ratchet wheel arranged at the right of said platen and operatively connected thereto, a pawl carrier pivoted on a vertical axis, said axis being to the right of said ratchet wheel and in rear of the platen axle, a pawl pivoted on said pawl carrier to swing in a vertical plane, said pawl being adapted to coöperate with the under side of said ratchet wheel, a spring tending constantly to swing said pawl upward, and means for regulating the normal height of the pawl tooth. 65
- tion of a platen carrier, a platen thereon, a line space ratchet wheel arranged at the right of said platen and operatively connected thereto, a pawl carrier pivoted on a vertical axis, said axis being to the right of said ratchet wheel and in rear of the platen axle, a pawl pivoted on said pawl carrier to swing in a vertical plane, said pawl being adapted to coöperate with the under side of said ratchet wheel, a spring tending constantly to swing said pawl upward, and means for regulating the normal height of the pawl tooth. 70
7. In a typewriting machine, the combination of a platen carrier, a platen thereon, a line space ratchet wheel arranged at the right of said platen and operatively connected thereto, a pawl carrier pivoted on a vertical axis to the right of said ratchet wheel and in rear of the platen axle, said pawl carrier being provided with a portion extending forward under the platen axle and terminating in a finger piece, a pawl mounted on said pawl carrier at the left of its axis, said pawl having a tooth coöoperative with the under side of said ratchet wheel, and a line space regulator mounted on said pawl carrier and coöoperative with said pawl to maintain it 80 normally at predetermined heights. 85
8. In a typewriting machine, the combination of a platen, a line spacing ratchet wheel connected thereto, a hand operated pawl carrier having a handle portion arranged under the platen axle and pivoted to swing in a path substantially parallel thereto, a pawl on said carrier pivoted to swing in a vertical path, said pawl being adapted to coöperate with said ratchet wheel but being normally separated therefrom, and means for limiting the extent of operative movement of said pawl carrier. 105
9. In a typewriting machine, the combination of a platen, a line spacing ratchet wheel connected thereto, a hand operated pawl carrier having a hand portion arranged under the platen axle and swingable in a path substantially parallel thereto, a pawl on said carrier movable in a vertical plane, said pawl being adapted to coöperate with said ratchet wheel but being normally separated therefrom, and an abutment on said pawl carrier adapted to coöperate with said line spacing wheel to limit the operative movement of said carrier. 110
10. In a typewriting machine, the combination of a platen carrier, a platen thereon, a line spacing ratchet wheel connected to said platen, a hand operated pawl carrier provided with an integral finger piece and 120
- 115
- 120
- 125
- 130

pivoted to swing transversely of said ratchet wheel, a pawl pivoted directly on said carrier to swing in a path substantially at right angles to the plane of movement of said carrier, a pawl regulator on said carrier for varying the normal height of the pawl tooth, a stop on said platen frame, a spring connected with said pawl carrier and normally maintaining it against said stop, and 10 a second stop on said pawl carrier coöoperative with said ratchet wheel for limiting the operative movement of said carrier.

11. In a typewriting machine, the combination of a platen carrier, a platen thereon, 15 a line spacing ratchet wheel connected to said platen, a bell crank lever pivoted on said platen carrier and having a vertical axis of rotation, a pawl pivoted directly on said bell crank and adapted to swing in a 20 substantially vertical path, said pawl co-operating with said ratchet wheel, a line space regulator coöoperative with said pawl to vary its action on said ratchet wheel, said regulator being pivoted directly on said bell 25 crank lever, a pawl spring, and a lever returning spring connected to said lever and to said platen carrier.

12. In a typewriting machine, the combination of a platen carrier, a platen thereon, 30 a line spacing ratchet wheel connected to said platen, a bell crank pivoted on said platen carrier and having a vertical axis of rotation, the longer arm of said bell crank extending forward and terminating in a 35 finger piece, a line spacing pawl coöoperative with said ratchet wheel, said pawl being pivoted to the shorter arm of said bell crank and having a horizontal axis of rotation, a line space regulator mounted on the shorter 40 arm of said bell crank, a pawl spring mounted on the shorter arm of said bell crank, and a restoring spring connected to said bell crank and to said platen carrier.

13. In a typewriting machine, the combination of a platen carrier, a platen thereon, 45

a line spacing ratchet wheel connected to said platen, a bell crank lever pivoted on a detachable vertical pivot pin supported on ears on the end bar of said platen carrier, the longer arm of said bell crank lever extending forward and being provided with a finger piece, the shorter arm extending inward through an opening in said end bar, a line spacing pawl pivoted to the shorter arm of said bell crank lever, a line space regulator mounted on the shorter arm of said bell crank lever, a pawl spring mounted on the shorter arm of said bell crank lever, stops for limiting operative movements of said bell crank lever, and a restoring spring for 60 said bell crank lever.

14. In a typewriting machine, the combination of a platen carrier, a platen thereon, a line spacing ratchet wheel connected to said platen, a bell crank lever pivoted on 65 said platen carrier and having a vertical axis of rotation, the longer arm of said bell crank lever extending forward and terminating in a finger piece, a line spacing pawl coöoperative with said ratchet wheel, said pawl being pivoted to the shorter arm of said bell crank lever and having a horizontal axis of rotation, a line space regulator mounted on the shorter arm of said bell crank lever, a spring for said pawl mounted 75 on the shorter arm of said bell crank lever, an abutment on the shorter arm of said bell crank lever, said abutment coöoperating with said ratchet wheel to limit operative movements of said bell crank lever, and a spring 80 connected at one end to said abutment and at its opposite end to said platen carrier.

Signed at the borough of Manhattan, city of New York, in the county of New York, and State of New York, this 1st day of April, A. D. 1913.
